UNITED STATES PATENT OFFICE

GEORGE A. ARMSTRONG, OF CRANSTON, RHODE ISLAND, ASSIGNOR TO WILLIAM C. GREENE COMPANY, A CORPORATION OF RHODE ISLAND

FINGER RING

Application filed February 8, 1932. Serial No. 591,483.

My invention relates to finger rings embodying a setting for a jewel, stone, or other ornament.

The essential objects of my invention are to enable in this type of ring a saving in the thickness of the stock in the ring head without the fact becoming apparent; to obviate the employment of an interior supporting shelf or annual bearing shoulder in the bezel portion of the head thus diminishing the excessive expense and labor of such construction, and rendering less laborious and expensive the accommodation of the ornaments of different thicknesses; and to reduce the number of ring parts exclusive of the ornament to two; and to insure a rigid and unyielding support for the ornament at all times. Other objects and advantages will be hereinafter apparent to one skilled in the art.

To the above ends essentially my invention consists in such parts and in such combinations of parts as fall within the scope of the appended claims.

In the accompanying drawing which form a part of this specification,

Figure 1 is a top plan view of a ring embodying my invention,

Figure 2, a section on line 2—2 of Figure 1,

Figure 3, a fragmentary section taken on line 3—3 of Figure 1, and

Figure 4, a perspective view of the ring prior to the application of the housing.

Like reference characters indicate like parts throughout the views.

As herein shown 6 is a band or annulus including the usual shank 7 and a laterally tapering and expanded head base 8 provided with a central orifice 9 and in this instance of reduced thickness to form resultant shoulders 10 adjacent the end of the shank, but the shoulders are not essential. The orifice may be of any preferred dimension or contour and is formed by centrally piercing and striking up the material of the base 8 to form a non-resilient vertical flange 11 provided upon its top edge with rigid vertically disposed substantially rectangular interspaced bearing lugs 12. In this case the lugs are four in number, disposed each upon one of the edges of a quadrilateral orifice.

The housing or cap 13, whose lower portion 14 is, as usual, of extended diameter and of uneven contour has its lower edge resting against the shoulders 10 and upon the peripheral margin of the base 8 where it is secured by solder concentric with the flange 11. An intermediate portion of the housing is of reduced diameter having an inwardly directed peripheral shoulder 16 integral with which is a vertical tubular portion or rim 18 whose free edge 19 is adapted to be engaged with the upper face of the stone, gem, or other ornament 21 by a knurling tool, bending, or otherwise.

The top of the lugs are in a horizontal plane 65 considerably below that of the edge 19 of the tubular portion 18, the distance being determined by the thickness of the particular ornament whose bottom face rests squarely upon the top edges of the lugs, which are at all 70 points interspaced from all portions of the housing.

The lug construction lends itself to the possibility of easily shortening the length of the lugs by suitable cutting tools to accommodate stones of either different or varying thickness. This is obviously effected before the operation of permanently applying the housing to the band structure shown in Figure 4. This construction also makes the 80 formation of internal peripheral supporting shoulders unnecessary and thus avoids the prohibitive expense of accommodating them to differing widths of ornaments supported thereby.

It will be noted that the annulus member 6 and housing member 13 are the only parts, aside from the ornament 21, necessary for assemblage.

It is important that the lugs 12 be perfectly vertical and rigid at all times, and a contributing element to this result is the presence of the flange 11. Without this flange the lugs might under strain bend to an inclined position, thus loosening the stone and admitting dirt to the setting or causing the ornament to escape.

I claim:

1. In a finger ring of the character described, a band comprising a shank and a 100

base continuous therewith provided with a central orifice, a peripheral vertical flange upon the base around the orifice, a housing upon the base exterior of the flange and concentric therewith, upright lugs integral with the upper edge of the flange and spaced from said housing, and an ornament supported by the housing resting upon the lugs.

2. In a finger ring of the character described, a band comprising a shank and a base provided with a central orifice, a peripheral vertical flange upon the base around the orifice, a housing upon the base exterior of the flange and concentric therewith including a tubular terminal portion, an engaging edge upon the extremity of the terminal portion, upright lugs integral with the upper edge of the flange extending to a plane below that of the engaging edge and spaced from said housing, and an ornament resting upon the lugs and engaged by said edge.

3. In a finger ring of the character described, a band comprising a shank and a base continuous therewith provided with a central orifice, a peripheral vertical flange upon the base surrounding the orifice, a housing for the flange fixed at its lower end to the base and including a tubular terminal portion, upright lugs integral with the flange and spaced from the housing, an ornament resting squarely upon the tops of the lugs, and an inturned edge upon the tubular portion of the housing engaging the upper face of the ornament.

4. In a finger ring of the character described a band comprising a shank and a base continuous therewith provided with a central orifice, a vertical peripheral flange integral with the base surrounding the orifice and having portions cut out to provide spaced lugs, a housing upon the base exterior of the flange and spaced from said flange, and an ornament upon the lugs engaged by the housing.

In testimony whereof I have affixed my signature.

GEORGE A. ARMSTRONG.
